Design No. 310.

JEWETT & ROOT'S

STOVE DESIGN

Patented July 9, 1850.

FIG. 1

FIG. 3.

FIG. 5

Mer 300

Sherman S. Jewett and
F. H. Root of Buffalo N. Y.
Letters Patent No. 300. Dated July 9, 1850.

The Schedule referred to in these Letters Patent & making part of the same.

To all whom it may concern:

Be it known that we, Sherman S. Jewett, and F. H. Root, of Buffalo, in the County of Erie, and State of New York have invented or produced a new and ornamental design for a Parlor Stove, of which the following is a full, clear, and exact description, reference being had to the accompanying drawing, which forms part of this specification, and in which figure 1 is an elevation of the front of the stove with the folding doors shut; figures 2 and 3 are elevations of the side plates; fig. 4 is

374
a plan of the top plate; and figure 5 is a plan of the bottom plate of the same.

The front plate of the stove is ornamented with a combination of figures composed of leaves (a) rosettes (b) and pendants (c) which surround its outer margin; the inner margin of the plate or that adjacent to the doors is also ornamented with leaves (d) united at the middle of the plate by a shell figure (e). The doors (A) are divided into panels by beading, and each panel is ornamented with an arabesque figure (f).

The side plates (figures 2 and 3) are paneled and each panel is ornamented with an arabesque figure (g) of leaves and buds.

The top plate of the stove (figure 4) is perforated at its middle; it is covered with a series of arabesque figures (h) consisting principally of leaves.

The bottom plate has its margin ornamented with leaves (i) the outer edges of which give shape to the edges of the plate.

What we claim as our invention and desire to secure by Letters Patent, is the shape and configuration of the ornamental plates for stoves herein described.

In testimony whereof we have hereunto subscribed our names.
